DRAFT ATTACHMENT FOR RAILWAY CARS
OR THE LIKEHarry H. Wolfe, Columbus, Ohio, assignor to The
Buckeye Steel Castings Company, Columbus,
Ohio

Application August 12, 1939, Serial No. 289,843

13 Claims. (Cl. 105—420)

This invention relates to improvements in draft attachments for railway cars and the like, and more particularly to improvements in the draft attachments disclosed in the application of George T. Johnson, Serial No. 193,783, filed March 3, 1938.

The primary purpose of the invention is to provide a novel draft attachment structure having a considerable saving in weight over the conventional riveted construction, either in grade "B" steel or high tensile steel.

Another object is to furnish a strong and durable draft attachment which eliminates plates heretofore employed, and therefore not only reduces weight but economizes on the time and the cost of welding.

A still further object is to supply a skeleton draft attachment including a bolster center filler designed to facilitate welding.

Another object is to provide a draft attachment so designed as to permit welding lugs to be secured to the webs of the center sills, such lugs filling partial slots in the castings.

Having now indicated in a general way the nature and purpose of the invention, I will proceed to a detail description thereof, with reference to the accompanying drawings, in which I have illustrated a preferred embodiment, and in which:

Fig. 1 is a top plan view partly in longitudinal horizontal section of the casting forming the bolster center filler.

Fig. 2 is a vertical sectional view of the same, taken on the line 2—2 of Fig. 1.

Fig. 3 is a front elevation partly in transverse vertical section.

Fig. 4 is a top plan view partly in horizontal section, and showing my improved striker casting and bolster center filler attached to the center sills.

Fig. 5 is a longitudinal vertical sectional view of the structure shown in Fig. 4.

Fig. 6 is an end view of the structure shown in Figs. 4 and 5, partially in transverse vertical section.

Referring first to the combined bolster center filler and rear draft lug casting shown in Figs. 1 to 3 inclusive, 7 designates the spaced vertical front walls of the casting which are of the full height of the casting, such walls being spaced apart and arranged at opposite sides of the pocket 8.

Such walls are connected to opposite top longitudinal horizontal ribs 9 by transverse ribs 10 which incline downwardly and forwardly from

the front ends of the ribs 9 and merge into the upper rear portion of the walls 7. Each rib 10 is reinforced by an upwardly extending rib 11 and a downwardly extending rib 12, the rib 11 merging into a front wall 7 and the rib 12 merging into the vertical cross tie 13 arranged at the rear of the pocket.

Rearwardly of the cross tie, the casting has transversely extending vertical ribs 14, 15 and 16 which merge at their lower ends into a horizontal plate 17, the latter being arranged at the middle of the casting and positioned above a similar bottom plate 18. The central portion of these plates are connected together by a king pin sleeve 19 from which radiates a forwardly extending rib 20, a rearwardly extending rib 21, and transverse ribs 22. The front end of the rib 20 merges into a transverse vertical wall 23, and the rib 21 merges at its rear end into a transverse vertical back wall 24.

A longitudinal medial rib 25 is provided at each side of the casting and merges at its front end into the medial portion of a wall 7, while its rear end merges into the plate 17.

Upwardly and downwardly projecting flanges 26 and 27 are arranged along the inner edge portion of each rib 25 for reinforcing purposes, and partial side walls 28 are arranged at the outer edge portions of the ribs 25 and merge into the walls 7 for reinforcing purposes. Each partial wall has notches or partial slots 29 and 30 for a purpose hereinafter described.

Bottom ribs 31 extend forwardly and upwardly from the wall 23 to the front walls 7, and each rib 31 is reinforced by a downwardly extending flange 32 and an upwardly extending flange 33, the former merging into one of the front walls and extending substantially the full length of the rib 31.

Rearwardly and upwardly extending ribs 33a join in the rear wall 24 to the top ribs 9, and the ribs 33a at the opposite sides of the casting are rigidly united by a rear tie bar 34.

In Figs. 4 and 5, I have indicated the manner in which such casting is welded to the center sills 35. As may be seen from these figures, the notches 29 and 30 receive relatively thick lugs 36 and 37 formed of welding metal which is secured to the side walls of the sills 35.

Each rib or flange 11 is welded to the top of a center sill by a line of welding 38 extending from a wall 7 to the rear of the gear pocket. Another line of welding 39 connects the side edge of the bottom of the rib 10 to a side wall 55 of a center sill. A broken line of welding 40

connects the bottom of each of the medial ribs 25 to a side wall of a center sill. A fillet weld 41 connects the lower portion of each wall 7 to a center sill, and the fillet weld extends rearwardly along the bottom of the bottom rib 31, and such weld is tapered rearwardly as indicated at 42.

Rearwardly of the cross tie 13, each of the top flanges 9 is welded at intervals to a center sill as indicated at 43. Other lines of welds 44 and 45 secure the side edges of the transverse ribs 14 and transverse wall 23 to the side walls of the center sills. Still other lines of welds 46 secure the side edges of the ribs 16 and rear transverse wall 24 to the side walls of the center sills. Welds 47 and 48 secure the outer edges of the inclined ribs 33a to the side walls of the center sills. Welds 13a secure the lateral edges of the tie bar 13 to the sills.

Tests on my improved design of casting and weld location have proved that the new construction is considerably stronger than those heretofore known, as the welds are now placed in compression and shear instead of tension and bending, and withstand dynamic shocks to better advantage.

Previous designs of center fillers have had lugs cast on the sides which extend through slots in the sills, and are then welded from the exterior of the latter. This method of attaching the casting to the sills has the disadvantage of necessitating slotting and weakening of the sills, and the difficulty of removing the casting from the sills if damaged by heavy buffing forces.

The new method of substantially welding lugs on the webs of the sills, filling partial slots or notches 29, 30 in the casting, eliminates the above disadvantages and in addition, the buffing forces on the draft lugs are distributed more directly to the sills.

As illustrated in Figs. 5 and 6, the use of notches or partial slots is of advantage in welding a striker casting 49 to the side walls of the sills, and as shown in Fig. 4, each notch 50 or a part of each slot 51 is filled with a lug 52 of welding metal employed in securing the casting firmly to the side walls of the sills.

While I have disclosed what I now consider to be a preferred embodiment of my invention in such manner that the same may be readily understood by those skilled in the art, I am aware that changes may be made in the details disclosed, without departing from the spirit of the invention, as expressed in the claims.

What I claim and desire to secure by Letters Patent is:

1. In a draft structure for railway cars or the like, center sills having spaced parallel substantially vertical walls, a metal skeletal casting extending between said walls, said casting being devoid of side walls except at one of its end portions, the side walls of the casting being provided with relatively deep notches, and lugs of welding metal occupying said notches and securing said casting to the walls of the center sills.

2. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of opposite side edge portions formed by substantially vertical transverse ribs and substantially horizontally disposed longitudinal ribs, the outer edge portions of said

ribs terminating at the inner surface of the walls of the center sills and being secured thereto by welded joints, co-planar spaced vertical front walls arranged at the forward end of the unit and merging into the side walls of the latter, the side walls of the unit being provided with relatively deep notches, and lugs of welding metal occupying said notches and securing said unit to the walls of the center sills.

3. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of side edge portions formed by substantially vertical transverse ribs and substantially horizontally disposed longitudinal ribs, the outer edge portions of said ribs terminating at the inner surface of the walls of the center sills and being secured thereto by welded joints, spaced vertical front walls arranged at the forward end of the unit and merging into the side walls of the unit, a pocket arranged at the front end of the casting between said vertical walls, and upwardly and rearwardly inclined ribs extending from said front walls to certain of said substantially horizontally disposed longitudinal ribs.

4. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of side edge portions formed by substantially vertical transverse ribs and substantially horizontally disposed longitudinal ribs, the outer edge portions of said ribs terminating at the inner surface of the walls of the center sills and being secured thereto by welded joints, spaced vertical front walls arranged at the forward end of the unit and merging into the side walls of the unit, a pocket arranged at the front end of the casting between said vertical walls, upwardly and rearwardly inclined ribs extending from said front walls to certain of said substantially horizontally disposed longitudinal ribs, and upwardly extending reinforcing flanges arranged at the inner edge portions of said inclined ribs and merging into said front walls.

5. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of side edge portions formed by substantially vertical transverse ribs and substantially horizontally disposed longitudinal ribs, the outer edge portions of said ribs terminating at the inner surface of the walls of the center sills and being secured thereto by welded joints, spaced vertical front walls arranged at the forward end of the unit and merging into the side walls of the unit, a pocket arranged at the front end of the casting between said vertical walls, upwardly and rearwardly inclined ribs extending from said front walls to certain of said substantially horizontally disposed longitudinal ribs, and downwardly extending flanges arranged at the inner edge portions of said inclined ribs and merging into said front walls.

6. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of opposite side edge portions formed by transverse ribs, the outer edge portions of said ribs terminating at the inner surfaces of the walls of the sills, certain of said edge portions being secured to the inner surfaces of the walls of the sills by welded joints, a pocket positioned at the front end portion of the unit, a transverse tie bar extending across the unit at the rear of said pocket, co-planar spaced vertical front walls arranged at the front end of the unit and merging into the side walls of the unit, upwardly and forwardly inclined bottom flanges merging at their front ends into said front walls and at their rear ends into certain of said transverse ribs, and fillet welds joining the side edges of said inclined ribs to the inner surfaces of the side walls of the sills.

7. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of opposite side edge portions formed by transverse ribs, the outer edge portions of said ribs terminating at the inner surface of the walls of the sills, certain of said edge portions being secured to the inner surfaces of the walls of the sills by welded joints, a pocket positioned at the front end portion of the unit, a transverse tie bar extending across the unit at the rear of said pocket, co-planar spaced vertical front walls arranged at the front end of the unit and merging into the side walls of the unit, upwardly and forwardly inclined bottom flanges merging at their front ends into said front walls and at their rear ends into certain of said transverse ribs, and fillet welds joining the side edges of said inclined ribs to the inner surfaces of the side walls of the sills, each fillet weld extending from one of the front walls rearwardly and gradually decreasing in thickness from said front wall rearwardly, and upwardly and downwardly projecting flanges arranged at the inner edge portions of said inclined ribs.

8. In a draft structure for railway cars or the like, center sills having spaced parallel substantially vertical walls, a skeletal cast metal combined bolster center filler and rear draft lug unit positioned between said walls, said unit being devoid of side walls except at its front end portion and having a multiplicity of opposite side edge portions formed by transverse ribs and terminating at the inner surfaces of said walls, certain of said edge portions being welded to the inner surface of said walls, co-planar spaced vertical front walls arranged at the front end of the unit and merging into the side walls of the unit, the side walls of the unit being provided with relatively deep notches, lugs of welded metal secured to said sills and substantially filling said notches, and upwardly and rearwardly inclined ribs extending rearwardly from the upper portions of said front walls and merging into certain of said transverse ribs.

9. In a draft structure for railway cars or the like, center sills having spaced parallel substantially vertical walls, a skeletal cast metal combined bolster center filler and rear draft lug unit positioned between said walls, said unit being devoid of side walls except at its front end portion

and having a multiplicity of opposite side edge portions formed by transverse ribs, the outer edge portions of said ribs terminating at the inner surface of the walls of the sills, certain of said edge portions being secured to the inner surfaces of the walls of the sills by welded joints, a pocket positioned at the front end portion of the unit, a transverse tie bar extending across the unit at the rear of said pocket, co-planar spaced vertical front walls arranged at the front end of the unit and merging into the side walls of the unit, upwardly and forwardly inclined bottom flanges merging at their front ends into said front walls and at their rear ends into certain of said transverse ribs, fillet welds joining the side edges of said inclined ribs to the inner surfaces of the side walls of the sills, each fillet weld extending from one of the front walls rearwardly and gradually decreasing in thickness from said front wall rearwardly, and upwardly and downwardly projecting flanges arranged at the inner edge portions of said inclined ribs.

10. In a draft structure for railway cars or the like, center sills having spaced parallel substantially vertical walls, a skeletal cast metal combined bolster center filler and draft lug unit positioned between said walls, said unit being devoid of side walls except at its front end portion, and comprising a central box-like portion having a king pin sleeve, transverse walls forming part of the unit and arranged forwardly and rearwardly of said sleeve, said transverse walls having side edge portions terminating at the inner surfaces of the walls of the sills and welded thereto, longitudinal medial ribs extending forwardly from the upper end of one of said walls and having side edge portions welded to the inner surfaces of the walls of said sills, upper substantially horizontal longitudinal ribs having side edge portions welded to said sills, and spaced vertical front walls merging into said ribs.

11. In a draft structure for railway cars or the like, center sills having spaced parallel substantially vertical walls, a skeletal cast metal combined bolster center filler and draft lug unit positioned between said walls, said unit being devoid of side walls except at its front end portion, and comprising a central box-like portion having a king pin sleeve, transverse walls forming part of the unit and arranged forwardly and rearwardly of said sleeve, said transverse walls having side edge portions terminating at the inner surfaces of the walls of the sills and welded thereto, longitudinal medial ribs extending forwardly from the upper end of one of said walls and having side edge portions welded to the inner surfaces of the walls of said sills, upper substantially horizontal longitudinal ribs having side edge portions welded to said sills, spaced vertical front walls merging into said ribs, and upwardly and forwardly inclined bottom ribs connecting one of the first-mentioned transverse walls to said front walls.

12. In a railway car, an integrally formed center sill reinforcing skeletal casting comprising a central box-like portion with a king pin sleeve and cored out opposite side walls, and vertically arranged front and rear end portions adapted to be welded to a structural steel member forming the center sill of the car, each of the front end portions being provided with a vertical front wall from which substantially horizontal ribs extend rearwardly to said central box-like portion, each front end portion being devoid

of a side wall except adjacent to said vertical front wall, and a tie bar connecting the rear end portions of the casting.

13. In a railway car, an integrally formed center sill reinforcing skeletal casting comprising a central box-like portion with a king pin sleeve and cored out opposite side walls, and vertically arranged front and rear end portions adapted to be welded to a structural steel member forming the center sill of the car, each of said front 10

end portions being devoid of any side wall except at the front end portion thereof, a vertical transversely extending front wall merging into each of said side walls, a tie bar rigidly connecting the rear end portions, and an upwardly and rearwardly inclined rib forming part of each rear end portion and merging at its ends respectively into said central box-like portion and said tie bar.

HARRY H. WOLFE.
